SLAT TILTING MECHANISM FOR VENETIAN BLINDS

Harry Nelson, New York, N. Y., assignor to
Lorentzen Hardware Mfg. Corp., New York,
N. Y., a corporation of New York

Application January 18, 1950, Serial No. 139,184

8 Claims. (Cl. 160—177)

1

This invention relates to Venetian blinds and, more particularly, to Venetian blind slat-tilting mechanism.

A Venetian blind is essentially a series of parallel articulated slats which are supported by two or more depending ladder tapes. Slat-tilting mechanism is provided which includes some type of horizontally pivoted tilt member at the top of the blind from which the ladder tapes are suspended. Since the slats of the blind are thin and more or less flexible, it is usual to provide a heavier slat or bottom bar at the lower ends of the ladder tapes. Lift cords are customarily provided for raising the bottom bar towards the tilt member when it is desired to raise the blind, the slats accumulating on top of the bottom bar as it is raised.

It is usual to provide a tilt, which is usually of the worm and gear type, for oscillating the tilt member so as to tilt the slats in either direction from level or blind-open position. There is usually some lost motion or play in the tilting mechanism due to normal operating clearance as well as normal wear of the parts. When the slats are in substantially level position, this play may be objectionable in that the wind at times has a tendency to vibrate or oscillate the slats and tilt member through this lost motion in an objectionable manner. When the slats are tilted in either direction from horizontal, they are biased towards the horizontal by the weight of the bottom bar since the bottom bar is raised somewhat as well as being tilted by the tilting of the slats. The force of the wind is not sufficient to overcome such bias, and thus the lost motion in the tilting mechanism is not then objectionable since the slats and the tilt member are not oscillated through the lost motion.

According to the present invention, frictional resistance is interposed against revolution of the tilt member when the slats are in substantially level position. As the slats are rotated in either direction from level position, the frictional resistance becomes inoperative so as to permit free turning of the slats and tilt member, thus contributing to an easy-operating blind. This is of particular importance in a blind having a so-called "escapement tilt" as disclosed in my Patent 2,174,994, issued October 3, 1939, in which the gear-sector may be rotated out of mesh with the worm to permit equalizing of the depending ends of the tilt cord. In such a construction, it is necessary that the tilt member and gear-sector freely rotate back into engagement with the worm to provide for remeshing of the worm and

2

gear after escapement has occurred. Such a tilt is, to all practical purposes, irreversible, in that torque imposed on the gear by pulling on the ladder tapes will not cause rotation of the worm.

5 In the form shown, the invention has been applied to an enclosed metal head bar construction of the type shown in my Patent 2,629,434 and embodying a tilt rod cradle of the type disclosed in my Patent 2,622,673, the tilt member being formed of a tilt rod and tape rockers generally similar to those shown in the former application. A portion of the tape rocker is offset to produce frictional engagement of the tape rocker against the cradle when the slats are in substantially level position, this frictional resistance disappearing as the tilt member is moved to rotate the slats in either direction from the horizontal.

20 An object of the present invention is to provide a Venetian blind head bar assembly in which the slats are held against idle movement, to provide such an assembly in which the slats are restrained against such idle movement only when in substantially level position, and to provide such an organization in conjunction with tilters of the escapement type.

Another object of the invention is to provide such an assembly which is simple and economical to manufacture and durable and dependable in operation.

25 Further objects and objects relating to details and economies of construction and operation will more definitely appear in the detailed description to follow.

30 35 My invention is clearly defined in the appended claims. In the claims, as well as in the description, parts are at times identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawings forming part of this specification, in which:

40 45 Fig. 1 is a front elevation of a Venetian blind embodying the present invention, the lower portion of the blind and a part of the front portion of the head bar being broken away.

50 Fig. 2 is a top plan view of the blind shown in Fig. 1, the lift cords and tilt cords having been omitted.

Fig. 3 is a vertical section of the tilt rod cradle, tape rocker and tilt rod taken on the line 3—3 of Fig. 2.

Fig. 4 is a horizontal fragmentary section of the assembly of Fig. 3 taken on the line 4-4 thereof.

Fig. 5 is an end view of the tape rocker.

Referring now to Figs. 1 and 2, the Venetian blind there shown comprises a head bar assembly of the enclosed-metal-head type, in which a channel-shaped sheet metal head bar 10 supports and encloses the operating mechanism of the blind. The operating mechanism within the head bar 10 includes a tilter 11 located adjacent one end of the head bar, a cord lock 12 located adjacent the other end of the head bar, and a pair of tilt rod cradles 14, 14 located between the tilter and cord lock and forming bearings for supporting a tilt rod extending lengthwise of the head bar and engaged with the tilter. A pair of drum-shaped tape rockers 16, 16 are mounted on the tilt rod 15, one above each tilt rod cradle 14, the tilt rod and tape rockers comprising a tilt member. The tilt rod 15 is preferably noncircular in cross section so as to nonrotatably engage a gear-sector contained within the tilter 11 and similarly engage the tape rockers 16, 16.

The slats 17 of the blind, two of which are shown in Fig. 1, are supported in parallel relation below the head bar 10 by a pair of ladder tapes 18, 18. The upper ends of the branches of the ladder tapes are led through slots 19 formed in the bottom wall of the head bar 10 and have terminal loops engaging one on each side of the tape rockers 16, 16 so as to suspend the ladder tapes and slats from the tilt member. Lift cords 20, 20, reeved through the cord lock 12 and the tilt rod cradles 14, 14, pass downwardly through holes (not shown) in the slats 17 of the blind, the ends of the lift cords being attached to the bottom bar.

A tilt cord 21 is reeved about a cord pulley 22 of the tilter, the two ends of the cord being led downward through a slot 24 in the bottom wall of the head bar. The tilter 11 is operated by pulling one or the other of the ends of the tilt cord 21 so as to rotate the cord pulley 22, and rotate the tilt rod 15 by means of a customary worm and gear sector mechanism.

The tilt rod 15 and tape rockers 16, 16 are shown in Figs. 1 and 2 in slat-level position, the tilt rod being oscillatable by the tilter 11 through a range of about 90° in either direction to operate the ladder tapes 18, 18 in unison so as to tilt the slats 17 to blind-closed position in either direction. In tilting the slats to blind-closed position in either direction, the center of gravity of the bottom bar is raised somewhat, the force of gravity serving to bias the tilt rod 15 and cradles 14, 14 towards slat-level position. This usual characteristic of Venetian blinds is made use of, in that the tilter 11 is preferably of the escapement type shown in my Patent No. 2,174,994 above referred to. The bias of the tilt rod serves to remesh the gear sector with the worm after escapement has occurred. The general head bar organization is shown and described in greater detail in my Patent 2,629,434.

The tape rocker 16, 16 each have a cylindrical or drum-like body 26 which is provided with fingers for engaging the looped ends of the branches of the ladder tapes 18, 18, the depending branches resting against the surface of the body. An end flange 27 is located at each end of the tape rocker body 26, this flange projecting inwardly and having an arcuate portion concentric with the axis of the body and provided with a noncircular opening corresponding in shape 75 towards

with the cross-section of the tilt rod 15. Preferably, the tape rocker end flanges 27, 27 are each provided with a circular outwardly pressed bead 30 concentric with the arcuate portion of the flange and spaced inwardly somewhat from the edge thereof, this bead serving as a bearing for the tape rocker against a vertical flange 25 of the associated tilt rod cradle 14.

The tilt rod cradles 14, 14 here shown are of the type shown in my Patent 2,622,673 in which a single vertical flange 25 at one end of the tape rocker 16 supports the tilt rod 15. Each tilt rod cradle 14 has a base portion 31 which is adapted to be secured to the bottom wall of the head bar 10 at each ladder tape 18. The cradle base 31 is provided with a cord guide pulley (not shown) facilitating leading the lift cord upwardly through the blind slats and longitudinally of the head bar.

The vertical flange 25 of each tilt rod cradle 14 projects upwardly from one end of the cradle base and has an upwardly opening semicircular bearing 34 for receiving and supporting the tilt rod 15. An inner side (towards the base) of the flange 25 adjacent the bearing 34 is flat and extends perpendicularly to the tilt rod in order to provide a smooth surface to be contacted by the circular bead 30 of the tape rocker 16 so as to limit endwise movement of the tape rocker in that direction. A finger or tab 35, which may be formed from the flange 25, overlies the end flange 27 of the tape rocker to limit endwise movement of the tape rocker in the other direction so as to keep the tape rocker centered over the cradle and the openings in the head bar provided for passage of the ladder tapes. Preferably, the tab 35 is located diametrically opposite the connection of the end flange 27 with the rest of the tape rocker body when the slats are in level position (as indicated in Fig. 3) to permit the tape rocker to be oscillated in both directions in excess of 90°. This organization is described more fully in my Patent 2,622,673.

According to the present invention, the tilt member, including in this instance the tilt rod 15 and the tape rockers 16, 16, is provided with a frictional resistance against rotation when the tilt member is in slat-level position. This may be accomplished by inwardly inclining or deforming the zone 38 of the arcuate portion of the end flange, which is under the tab 35 when the tape rocker is in slat-level position so that the end flange will bind between the tab and the rest of the vertical flange 25. The degree of inclination or deformation is chosen so as to offer sufficient resistance to rotation of the tape rocker to prevent vibrational oscillation of the blind slats and the tilt member by the wind, but to permit easy manual tilting of the slats in the usual manner by means of the tilt cord 21 and tilter 11. Preferably, each end flange 27 of each tape rocker 16 is similarly formed to facilitate assembly, in that the tape rocker 16 may then be assembled without regard to which end is associated with the vertical flange 25 of the cradle 14.

While the frictional resistance against tilting of the blind could be made operative regardless how far the slats were tilted, such as arrangement has certain disadvantages in that, as the slats are tilted in either direction from the horizontal, they become harder to tilt due to the fact that such tilting tends to raise the center of gravity of the bottom bar and the force of gravity acting thereon tends to bias the blind towards slat-level position. Thus, interposing

frictional resistance only when the slats are in substantially level position tends to equalize the force required to tilt the blind, regardless of slat position. Further, when Venetian blinds are equipped with escapement tilters of the type in which the gear segment is permitted to run out of mesh with the worm to compensate for slippage of the tilt cord on the cord pulley, it is essential that the tilt member be free to rotate when the slats are tilted to a maximum in either direction to insure remeshing of the worm and gear. Since, when the slats are tilted from horizontal position in either direction, the slats and tilt member are biased towards such level position, this bias will serve effectively to prevent vibration of the slats and tilt member due to action of the wind.

I claim:

1. In a Venetian blind of the enclosed-head type having a channel-shaped head bar provided with fittings for supporting a longitudinally extending tilt rod, including a tilter of the worm and gear type in which the gear may be run out of mesh with the worm and two or more tilt rod cradles, and in which a tape rocker is mounted on a tilt rod adjacent each cradle, the improvement which comprises: at least one of the tape rockers having a generally circular end flange concentric with the axis of rotation of the tilt rod and the adjacent cradle having an upstanding flange provided with portions extending closely adjacent both sides of the end flange of the tape rocker, a portion of the end flange of the tape rocker being of such axial extent as to frictionally bind between the adjacent portions of the cradle when the slats are in substantially level position, the remainder of the end flange of the tape rocker beyond the zone of said first-mentioned portion being of lesser axial extent than the flange-receiving space between the portions of the cradle, so that the binding portions of tape rocker and tilter is moved out of engagement upon rotation of the tape rocker to move the slats towards blind-closed position.

2. In a Venetian blind, a slat tilting mechanism including a horizontally pivoted tilt member, a plurality of slats suspended in parallel relation from said tilt member, and a pair of elements, one of said elements being stationary and the other of said elements being rotatable with the tilt member, the rotatable element rotating on a fixed axis and having a surface which frictionally engages the stationary element when the slats are in substantially level position to interpose a frictional resistance to rotation of the tilt member, said surface of the rotatable element being free from contact with the stationary element at zones a relatively short distance on either side of the mid-point of such surface, so that such elements cease to interpose a frictional resistance to rotation of the tilt member as the slats are moved from slat-level towards blind-closed position.

3. In a Venetian blind, a head bar, a plurality of tilt rod cradles mounted thereon, a longitudinally extending tilt rod journaled in said cradles, a plurality of tape rockers mounted on the tilt rod, a plurality of slats suspended in parallel relation from said tape rockers, an irreversible tilter of the worm-and-gear type connected with the tilt rod, and means for frictionally resisting rotation of the tilt rod when the tilt rod is in slat-level position and for allowing the tilt rod to be freely rotated by the tilter throughout a substantial range on either side of slat-level posi-

tion including each terminal tilted position of the tilt rod, said last-named means comprising a first element formed on an end flange of one of the tape rockers, a second element formed on the tilt rod cradle adjacent to and cooperating with the first element, the first element having an extended frictional surface forming a cam and the second element being frictionally engageable with said cam, the elements being so located with respect to the tilt member, the head bar, and each other that, at slat-level position of the tilt member, the second element engages the cam at substantially the mid-point of the latter, the cam terminating and becoming disengaged from the second element at zones of disengagement a relatively short distance on either side of such mid-point of the cam, the second element remaining disengaged from the cam throughout the range of tilt-tilting beyond such zone of disengagement on either side of slat-level position.

4. In a Venetian blind of the enclosed head type having a channel-shaped head bar provided with a tilter of the worm-and-gear type in which the gear may be run out of mesh with the worm, two or more tilt rod cradles, a tilt rod rotatably supported in said cradles and a tape rocker mounted on the tilt rod adjacent each cradle, the improvement which comprises: at least one of the tape rockers having a generally flat, circular end flange concentric with the axis of rotation of the tilt rod, the cradle adjacent said tape rocker having an upstanding flange provided with opposed portions extending closely adjacent both sides of the end flange of the tape rocker, a portion of the periphery of the end flange of the tape rocker being axially displaced so as to frictionally bind between the adjacent portions of the cradle when the slats are in substantially level position, the remainder of the end flange of the tape rocker beyond the ends of the first portion being of lesser axial dimension than the distance between the opposed portions of the cradle, the binding portions of the tape rocker and cradle being moved out of engagement upon rotation of the tape rocker to move the slats towards blind-closed position.

5. In a Venetian blind: a head bar, a longitudinally extending tilt member having a generally radially extending flange, a plurality of slats suspended in parallel relation from said tilt member, a tilter connected with the tilt member, and an element fixed on the head bar adjacent to and cooperating with the radially extending flange of the tilt member, the radially extending flange having a portion of greater axial extent binding against the fixed element at slat-level position of the tilt member to set up added frictional resistance against oscillation of the tilt member, the portion of said flange of greater axial extent moving out of engagement with said element as the slats of the blind are tilted slightly in either direction from slat-level position.

6. In a Venetian blind: a head bar, a longitudinally extending tilt member having a generally radially extending flange, a plurality of slats suspended in parallel relation from said tilt member, a tilter connected with the tilt member, and an element fixed on the head bar and having a slot formation receiving the radially extending flange of the tilt member, said radially extending flange having a portion of greater axial extent binding within said slot formation at slat-level position of the tilt member to set up added frictional resistance against oscillation of the tilt member, the portion of said flange of greater

7. axial extent moving out of engagement with the slot formation of the fixed element as the slats of the blind are tilted slightly in either direction from slat-level position.

7. In a Venetian blind as set forth in claim 6, 5 the tilter being of the worm-and-gear type in which the gear may be run out of mesh with the worm at blind-closed positions of the slats.

8. In a Venetian blind as set forth in claim 2, 10 the slat-tilting mechanism also including a tilter of the worm-and-gear type in which the gear

may be run out of mesh with the worm at blind-closed positions of the slats.

HARRY NELSON.
